(57) **CLAIM**

The ornamental design for a jacket, as shown and described.

DESCRIPTION

FIG. 1 is a perspective view of a front and a right side of a jacket design;

FIG. 2 is a front elevational view of the jacket from FIG. 1;
FIG. 3 is a rear elevational view of the jacket from FIGS. 1-2;
FIG. 4 is a left side elevational view of the jacket from FIGS. 1-3;

FIG. 5 is a right side elevational view of the jacket from FIGS. 1-4;

FIG. 6 is a top plan view of the jacket from FIGS. 1-5; and,
FIG. 7 is a bottom plan view of the jacket from FIGS. 1-6.
The broken lines are for the purposes of illustrating environment only. None of the broken lines form part of the claimed design.
